UNITED STATES PATENT OFFICE.

HUGO BRINKHAUS, OF BROOKLYN, NEW YORK.

BOAT.

1,271,499.

Specification of Letters Patent.

Patented July 2, 1918.

Application filed July 7, 1916. Serial No. 107,914.

To all whom it may concern:

Be it known that I, HUGO BRINKHAUS, a citizen of the United States, residing at the borough of Brooklyn, in the county of Kings and State of New York, have invented certain new and useful Improvements in Boats, of which the following is a specification, reference being had therein to the accompanying drawings, forming part thereof.

10 My invention relates to boats of all kinds and relates more particularly to means for increasing the speed and economizing the power. The main object of my invention is to reduce or decrease the head resistance or 15 bow resistance of boats of all kinds from the largest ocean liner down to the smallest craft. Other more particular objects and advantages of my invention will hereinafter appear.

20 My invention includes one or more water-conveying conduits arranged longitudinally fore and aft or lengthwise of the boat outside of the hull of the boat, such, for example, as one such conduit at each side of 25 the hull below the water line and adjacent to the bottom of the boat, one side of each conduit conforming to the contour of the hull of the boat, that is to say, the hull of the boat forming the inner wall of the conduit and the other side walls of the conduit, that is, the upper, lower and outer walls thereof, being parallel to the longitudinal axis of the boat, each such water-conveying 30 conduit extending fore and aft and preferably extending from a point even or flush with the extreme front end or prow of the boat, aft or back nearly to or substantially to the stern of the boat, so that water-collecting or water-receiving funnels are provided 35 at the bow of the boat and water-releasing or water-discharging funnels are provided at the stern of the boat; means, such as propellers within the conduits being provided for impelling the water through the conduits 40 from end to end thereof, for overcoming the skin-friction of the water therein and so that a substantial part of the water at the front of the boat which otherwise would have to be pushed out of the way by the advancing boat and which would be raised to the surface and rolled away in a bow wave, will be removed from in front of the boat and will be carried sternward through the conduits, thereby decreasing the bow resistance 45 or head resistance and at the same time propelling or assisting in propelling the

boat forward. My invention further includes features of construction and combinations of parts as will appear from the following description.

I shall now describe the sea-going boat or ocean liner illustrated in the accompanying drawings as embodying my invention and shall thereafter point out my invention in claims.

Figure 1 is a plan view with the hull of the boat appearing in outline and embodying my invention.

Fig. 2 is a starboard side elevation, the hull only of the boat appearing, the superstructure and other parts being omitted.

Fig. 3 is an elevation of the bow of the boat as viewed from the right in Figs. 1 and 2, the grating there appearing being omitted.

Fig. 4 is a transverse section on a vertical plane indicated by the line 4—4 of Figs. 1 and 2 as viewed from the left.

Fig. 5 is a stern view or elevation as viewed from the left in Figs. 1 and 2.

Fig. 6 is a cross-sectional view similar to Fig. 4, but with parts omitted and looking in the opposite direction, of a modified construction having two water-conveying conduits one above the other at each side of the hull of the boat.

The boat illustrated in the accompanying drawings as embodying my invention is an ocean liner of a typical or usual design, the hull only being shown and comprising sides or side walls 1 and 2 and a bottom 3. The boat is shown as provided with usual twin screw propellers 4 and with a usual rudder 5. It is to be noted that, so far as my invention is concerned, the contour, shape or design of the hull of the boat in which my invention is embodied may be different from that illustrated in the accompanying drawings and may be of any usual or suitable configuration or design. It is not the purpose of my invention in any way to alter or change the hull design of boats, such as ships or other water craft, now in use to which my invention may be applied or in which it may be embodied. In fact my invention may be initially embodied in the construction of new vessels, or it may be later applied to and embodied in vessels which were originally built without my invention.

In carrying out my invention in the embodiment thereof illustrated in the accom-

panying drawings similar right and left homologous water-conveying conduits are provided respectively at the port and starboard sides of the hull running lengthwise 5 along and fore and aft from the bilge adjacent to and upward from the bottom 3 of the boat and located below the water line WL, as appears in the several figures of the drawings. These water-conveying conduits are 10 shown as of substantially U-shape in cross-section. The hull of the boat at the sides thereof upward from the bottom 3 forms the inner wall of each of these conduits and all of the other inclosing walls of the conduits, that is to say, their outer and upper and 15 lower walls run along straight lines fore and aft parallel with the longitudinal axis of the boat, so that the gradual taper and usual slight overhang of the bow of the 20 boat at the front, and the usual considerable overhang and slight taper of the hull at the stern, provide, respectively, inwardly tapered water-receiving or water-collecting and outwardly flaring water-releasing or 25 water-discharging funnels at the opposite ends of the water-conveying conduits.

The shape or contour of the hull of the boat at its sides 1 and 2 adjacent to the bottom 3 gives to each water-conveying conduit 30 a middle reduced part which projects laterally or substantially horizontally from the lower part of the sides 1 and 2 upward from the bottom 3 along the bilge of the boat, and which besides forming a water-conveying conduit also constitutes a hollow bilge-keel for the boat. The cross-sectional shape of each of these conduits along its reduced middle part is substantially flat along its inner wall, which is formed by the wall 1 or 2 of 35 the hull of the boat, but the outer walls 6 of each of these conduits are shown as curved along nearly circular lines to the shape of a shallow letter U, and are joined to the hull of the boat.

45 The walls 6 of the reduced middle part of each of the conduits are extended forward to the extreme front end or prow of the boat, and at the bow of the boat the lower walls of these water-conveying conduits are shown as extended inward in line 50 with the bottom 3 of the boat to form at the bow of the boat lower walls 7 which are joined to the hull of the boat and, at the extreme front, to each other, and which are 55 shown as inclined slightly downward in harmony with or in conformity to the usual slight inclination of the bottom 3 toward the keel line. This forwardly extending continuation or extension of the reduced 60 middle part of each water-conveying conduit has its upper wall shown as extended at an inclination upward and inward along lines or in a plane parallel to the course of the boat or parallel to the longitudinal axis 65 of the boat to form an upper wall 8, these

walls 8 being joined to the hull of the boat along the tapered bow, as appears in the drawings.

The forwardly flaring water-receiving and water-collecting funnel part of each of the 70 water-conveying conduits at its forward end is preferably, as shown in the drawings, flush or substantially flush with the extreme front end or bow of the boat. This forward water-collecting flaring part of each of these 75 conduits comprises the lower slightly inclined bottom wall 7, the upper inclined flat wall 8, and the intervening or intermediate connecting curved wall 6, which, as shown and above described, is extended forward 80 from the reduced part of the conduits at the bilge of the boat.

The curved conduit-forming wall 6 is shown as extending rearward or sternward from the bilge nearly to the stern of the 85 boat and is shown as terminating at a point slightly in advance of the usual propeller 4 and at the side of the usual short stern keel 9 of the boat. The rearwardly flaring water-releasing or water-discharging funnel part 90 of the conduit is formed by a lower wall 10 extending inward from the curved outer wall 6 in line with the bottom 3 of the boat, similarly to the forward bottom wall-extension 7 and similarly joined to the hull of 95 the boat; and an upper wall 11 which is shown as extended at an inclination upward and inward from the curved wall 6 till it joins the hull of the boat along curved lines throughout its length, the wall 11, however, 100 being disposed in a plane parallel to the longitudinal axis of the boat.

It is to be noted in the construction illustrated, as appears in Fig. 5 and as is indicated by dotted lines in Fig. 1, that the 105 upper wall 11 at the stern does not reach the keel line of the boat, this being by reason of the fact that this wall at the stern end of the conduit part formed thereby terminates at a point slightly forward from the 110 stern of the boat where the hull of the boat has a substantial thickness more than that of the stern keel 9. It is also to be noted that the rear upper walls 11 are inclined upwardly at a slightly greater angle than the 115 upper forward walls 7, so that, in the construction illustrated in the drawings, the capacities or cross-sectional areas of the forward ends of these water-conveying conduits and of the rear or stern ends thereof are substantially equal. It is to be further noted that not only does the curved wall 6, forming the middle reduced part 120 of each of the conduits, constitute a hollow bilge keel, but that also the fore and aft extensions of this wall, and also together therewith the inwardly extended upper and lower forward walls 7 and 8 and the similar inwardly extended upper and lower rear walls 10 and 11 form extensions of 125 130

such bilge keel and have a similar keel-forming function in addition to their function of receiving or collecting and conveying the water away from the bow of the boat and releasing or discharging it at the stern.

The collecting of water at the bow and discharging at the stern is, of course, to a large extent only apparent, as in reality, due to the forward movement of the boat caused by the usual propellers 4, the water in the conduits at the bow and stern of the boat is substantially at a standstill, while a rapid movement of the water in the narrower portions of the conduits, from the front to the rear, reduces the frontal resistance of the boat to the amount of the capacity of the funnels.

Means are provided for impelling the water through the above described water-conveying conduits and such water impelling means, as illustrated in the drawings, may be screw propellers 12 located within the reduced part of each conduit at the bilge of the boat. These inclosed water-impelling propellers 12 are shown as four in number, two within the middle reduced part of each of the water-conveying conduits, one in advance of the other. These propellers 12 are shown as arranged at an angle or inclination, having propeller shafts 13 the axes of which are all in the same horizontal plane, but which are in different vertical planes which are slightly inclined at an acute angle to the vertical keel plane of the boat, so that these propeller shafts 13 converge in a forward direction from the propellers 12 and enter the hull of the boat through the sides 1 and 2 thereof, for the connection thereto of a suitable prime mover or power-providing means within the hull of the boat, in a manner or of a construction similar to the usual driving means for the usual propellers 4, or by any other suitable means. Bearing-providing ribs or ridges 14 are provided on the sides 1 and 2 of the hull for the propeller shafts 13, similar in this respect to the usual bearing-providing ridges or ribs 15 for the shafts 16 of the usual propellers 4. The slight inclination of the inclosed propellers 12 within the narrower part of each of the water-conveying conduits does not substantially interfere with their effectiveness or efficiency and provides a very simple construction without any substantial obstruction of the water-conveying conduits and also provides for the convenient application of power to the propeller shafts 13 to drive the water-impelling propellers 12.

It should be noted that the highest points of each of the water-conveying conduits, namely, the upwardly inclined and inwardly extended top wall 8 at the bow of the boat and the similarly upwardly inclined and inwardly extended top wall 11 at the stern of the boat, are still well below the

water line WL. It is further to be noted that the fore and aft upwardly and inwardly inclined top walls 8 and 11 could be thus inclined upwardly either more or less than appears in the drawings to correspondingly vary the intake and discharge capacity or cross-sectional area of the fore and aft ends of the water-conveying conduits. Also these walls 8 and 11 do not need to be transversely straight or flat walls, as appears in the drawings, but could be of any other transverse or cross-sectional shape found desirable, care always being taken, however, that these walls, as well as all of the outer walls of these conduits, shall extend in straight and parallel lines fore and aft, so as to move longitudinally through the water and to gather in and convey sternward the water that otherwise would need to be pushed aside from the same space by the advancing tapering bow of the boat.

In the embodiment of the invention illustrated in the drawings, I have shown the propellers 12 at the sides of the boat within the above described water-conveying conduits as in addition to the usual propellers 4. In such a construction the propulsive effect of the usual propellers 4 may, if desired, be assisted by the propellers 12. In such case the water impelled sternward and discharged through the rear ends of the water-conveying conduits will react directly upon the surrounding water. However, the propulsive effect of the propellers 12 will be helpful to the propellers 4 to a far greater extent by reason of the taking away or removal of a substantial part of the water from in front of the boat at the bow, thereby lessening the head resistance or bow resistance so that much less power will be required to propel the vessel forward.

From the foregoing description it will be apparent that the forward parts of the water-conveying conduits are of vastly greater importance than those parts thereof which extend aft. In fact, in some cases it may be found advisable to omit more or less of the length of these conduits from the stern end thereof. It is the forwardly flared or funnel shaped forward ends of these conduits which collect or gather in and remove sternward the water from in front of the bow of the boat which otherwise would impede the passage of the boat through the water, and in this connection it is to be noted that this water which is removed is taken away from the deeper levels thereof where the pressure of the water upon the hull of the boat is greatest and which deep lying water otherwise would have to be forced upward to the surface through or with the overlying water, and would be piled up, as is well known, at the bow of the boat and rolled away in the form of bow waves, with consequent waste of driving power.

4
 The outwardly flaring rear end parts or water-discharging funnels at the stern have their chief utility in directly aiding the propulsion of the vessel. By reason of this flaring construction, while still preserving outwardly straight fore and aft lines parallel to the axis of the boat, there is provided an enlarged area of the surrounding outside water for the sternwardly impelled water to act upon, effectively doing away with anything approaching to or resembling a jet, it being well known in the art that jet propulsion is ineffective. In my illustrated construction, as hereinbefore noted, the water leaving the stern ends of the water-conveying conduits will be substantially stationary with respect to the outer surrounding water. Similarly, as hereinbefore and also hereinafter noted, the water which enters the forward ends of these conduits will be likewise substantially stationary with regard to the surrounding water.

In carrying out my invention as illustrated in the accompanying drawings, the cross-sectional area of the fore and aft ends of the water-conveying conduits being substantially equal, as hereinbefore noted, the speed of travel of the water through these conduits will be substantially the same at its point of entrance or ingress at the bow of the boat and at its point of egress or discharge adjacent to the stern of the boat, and theoretically at least, or perhaps in practice with a particular design and with the use of the additional usual propellers such as 4, the water at its point of entrance or ingress to the water-conveying conduits at the bow of the boat and also such water at its point of discharge or egress adjacent to the stern of the boat could be substantially stationary relatively to the surrounding body of water, the water contained within the conduits having movement only in the more restricted intermediate parts of such conduits. The side propellers 12 within the reduced middle part of the water-conveying conduits may of course be reversed similarly to the reversal of the usual propellers 4, and also these inclosed propellers 12 may be employed, if desired, for steering purposes or for turning the boat around, or for stopping quickly in case of need. In some cases it may be found desirable to omit the usual propellers 4 and to rely wholly upon the water-conveying propellers 12 for the propulsion of the boat. Also in some cases, particularly when the usual propellers such as 4 are employed, it may be found desirable to omit one of the two propellers shown within the water-conveying conduits and to employ only one of these propellers within each such conduit. Likewise, of course, should it be found desirable for any reason, the number of propellers 12 within the wa-

ter-conveying conduits may be increased in number, as well as decreased.

Gratings 17 and 18 are provided respectively at the bow and stern of the boat for the water-conveying conduits to prevent the entrance into these conduits of anything which might choke them or injure the propellers 12 therein, the forward grating 17 being omitted in Fig. 3. The stern gratings 18, in the particular construction illustrated in the drawings, are located just within the rear ends of the conduits, and therefore do not appear in Figs. 1 and 2, but are seen from the stern in Fig. 5.

The modified construction illustrated in Fig. 6 has two water-conveying conduits 19 and 20, one above the other at the side of the boat, the upper conduit 20 being smaller and of correspondingly less capacity than the lower conduit 19. The lower and upper conduits 19 and 20 contain water-imelling propellers 21 and 22 similar to the propellers 12, hereinbefore described. In some cases, particularly should the usual propellers 4 be omitted, it may be found desirable to have two of the water-conveying conduits at each side of the boat, such as shown in Fig. 6. In other respects than as above noted, the construction illustrated in Fig. 6 may be substantially the same as that hereinbefore described with reference to the preceding figures of the drawings.

It is obvious that various modifications may be made in the constructions shown in the drawings and above particularly described within the principle and scope of my invention.

I claim:

1. A device for decreasing the head resistance of boats comprising a water-conveying conduit extending fore and aft outside of the hull of the boat from adjacent to the prow of the boat aft at least as far as the largest cross-sectional area of the boat and flaring at its forward end to provide a water-collecting funnel adjacent to the prow of the boat, and means for impelling the water sternward through such conduit.

2. A device for decreasing the head resistance of boats comprising, in combination with a boat having a forwardly tapering hull, a water-conveying conduit outside of the hull of the boat and one side of which conforms to the contour of the outside of the hull of the boat and the other side walls of which are longitudinally parallel to the longitudinal axis of the boat so as to present a forwardly flaring water-collecting funnel at the forward end of such conduit, and means for impelling the water sternward through such conduit.

3. A device for decreasing the head resistance of boats comprising, in combina-

- tion with a boat having a forwardly tapering hull, a water-conveying conduit at each side of and at the outside of the hull of the boat extending fore and aft from adjacent 5 the prow aft at least as far as the largest cross-sectional area of the boat and one side of which conforms to the contour of the outside of the hull from the bottom of the boat upward and the other side walls of 10 which are longitudinally parallel to the longitudinal axis of the boat so as to present a forwardly flaring water-collecting funnel at the forward end of each such conduit, and means within such conduits for impelling 15 the water sternward through the conduits.
4. A device for decreasing the head resistance of boats comprising, in combination with a boat having a hull tapering fore and aft, a water-conveying conduit at each side 20 of and at the outside of the hull of the boat extending fore and aft substantially from the prow aft adjacent to the stern at each side of the hull and one side of which conforms to the contour of the side of the hull 25 from the bottom upward and the other side walls of which are parallel to the longitudinal axis of the boat so as to provide at the prow a forwardly flaring water-collecting funnel and at the stern a rearwardly flaring 30 water-discharging funnel, and means within such conduits for impelling the water sternward therethrough.
5. A device for decreasing the head resistance of boats comprising, in combination 35 with a boat having a forwardly tapering hull, a water-conveying conduit at each side of and at the outside of the hull of the boat extending fore and aft from adjacent the prow aft beyond the widest part of the boat 40 at the bilge and one side of which conforms to the contour of the side of the hull from the bottom upward and the other side walls of which are longitudinally parallel to the longitudinal axis of the boat so as to provide 45 at the prow a forwardly flaring water-collecting funnel, and means within such conduits at the bilge of the boat for impelling the water sternward through the conduits.
- 50 6. A device for decreasing the head resistance of boats comprising, in combination with a boat having a hull tapering fore and aft, a water-conveying conduit at each side of and at the outside of the hull of the boat 55 extending fore and aft substantially from the prow aft beyond the bilge adjacent to the stern at each side of the hull and one side of which conforms to the contour of the side of the hull from the bottom upward 60 and the other side walls of which are parallel to the longitudinal axis of the boat so as to provide at the prow a forwardly flaring water-collecting funnel and at the stern a rearwardly flaring water-discharg-
- ing funnel, and means within such conduits at the bilge of the boat for impelling the water sternward through the conduits. 65
7. A device for decreasing the head resistance of boats comprising a water-conveying conduit at the outside of each side of the hull of the boat forming externally to the hull a hollow bilge-keel open fore and aft, and means for impelling the water sternward through such conduits. 70
8. A device for decreasing the head resistance of boats comprising a water-conveying conduit at each side of the hull of the boat forming a hollow bilge-keel and extending forward from the bilge toward the prow of the boat, the upper and lower walls of such 75 forwardly-extending part being continued inward to join the hull of the boat for presenting water-collecting funnels at the bow of the boat, the hull of the boat forming one of the walls of each conduit and all of 80 the other walls thereof being parallel to the longitudinal axis of the boat, and means at the bilge for impelling the water sternward through such conduits. 85
9. A device for decreasing the head resistance of boats comprising a water-conveying conduit at each side of the hull of the boat forming a hollow bilge-keel and extending both fore and aft from the bilge, the upper 90 and lower walls of such forwardly and rearwardly extending parts being continued inward to join the hull of the boat for providing water-collecting and water-discharging funnels respectively at the bow and at the stern of the boat, the hull of the boat forming one of the walls of each conduit and all of 95 the other walls thereof being parallel to the longitudinal axis of the boat, and means at the bilge for impelling the water sternward through such conduits. 100
10. A device for decreasing the head resistance of boats comprising a water-conveying conduit at each side of the hull of the boat forming a hollow bilge-keel and extending forward from the bilge toward the prow of the boat, the bottom wall of such 105 forwardly extended part being continued inward to join the hull of the boat and the top wall thereof being continued upward and inward to join the hull of the boat for providing a forwardly and upwardly flaring water-collecting front end of such conduit, the hull of the boat forming one of the walls of each such conduit and all of 110 the other walls thereof being parallel to the longitudinal axis of the boat, and means at the bilge for impelling the water sternward through such conduits. 115
11. A device for decreasing the head resistance of boats comprising a water-conveying conduit at each side of the hull of the boat forming a hollow bilge-keel and extending both fore and aft from the bilge, the bot- 120 125

6
tom wall of such forwardly and rearwardly extended parts being continued inward to join the hull of the boat and the top wall of such forwardly and rearwardly extended parts being continued upward and inward to join the hull of the boat for providing at the bow a forwardly and upwardly flaring water-collecting funnel and at the stern a rearwardly and upwardly flaring water-discharging funnel, the hull of the boat forming one of the walls of each such conduit and all of the other walls thereof being parallel to the longitudinal axis of the boat, and means at the bilge for impelling the water sternward through such conduits.

12. A device for decreasing the head resistance of boats comprising a water-conveying conduit at each side of and at the outside of the hull of the boat and extending aft from adjacent to the prow of the boat, the upper and lower walls of such conduit being joined to the hull of the boat so that the hull forms the inner wall of the conduit, all the other walls of the conduit being parallel to the longitudinal axis of the boat, whereby forwardly flaring water-collecting funnels are provided at the bow of the boat, and means for impelling the water sternward through such conduits.

13. A device for decreasing the head resistance of boats comprising a water-conveying conduit extending fore and aft outside of the hull of the boat substantially from the stem to stern, and a propeller within the conduit for impelling the water therethrough.

14. In the propulsion of boats, in combination, a water-conveying conduit arranged lengthwise of the boat at the outside of the hull thereof with its ends below the water-line and extending substantially from stem to stern and open at both ends, and means for impelling the water through the conduit.

15. In the propulsion of boats, in combination, a water-conveying conduit arranged lengthwise of the boat at each side thereof at the outside of the hull with its ends below the water-line and extending substantially from stem to stern and open at both ends, and means for impelling the water through these conduits from end to end thereof.

16. In the propulsion of boats, in combination, a water-conveying conduit arranged lengthwise of the boat at the outside of the hull thereof below the water-line and extending substantially from stem to stern and open at both ends, and means for impelling the water through the conduit.

17. In the propulsion of boats, in combination, a water-conveying conduit arranged lengthwise of the boat at each side thereof at the outside of the hull below the water-line and extending substantially from stem to stern and open at both ends, and means

for impelling the water through these conduits from end to end thereof. 65

18. A device for decreasing the head resistance of boats comprising a water-conveying conduit at the outside of each side of the hull of the boat forming externally of the hull a hollow bilge-keel open fore and aft.

19. A device for decreasing the head resistance of boats comprising a water-conveying conduit at each side of the hull of the boat forming a hollow bilge-keel and extending forward from the bilge toward the prow of the boat, the upper and lower walls of such forwardly-extending part being continued inward to join the hull of the boat 75 for presenting water-collecting funnels at the bow of the boat, the hull of the boat forming one of the walls of each conduit and all of the other walls thereof being parallel to the longitudinal axis of the boat. 80

20. A device for decreasing the head resistance of boats comprising a water-conveying conduit at each side of and at the outside of the hull of the boat and extending aft from adjacent to the prow of the boat, the upper and lower walls of such conduit being joined to the hull of the boat so that the hull forms the inner wall of the conduit, all the other walls of the conduit being parallel to the longitudinal axis of the boat, whereby forwardly flaring water-collecting funnels are provided at the bow of the boat. 90

21. A device for decreasing the head resistance of boats comprising a water-conveying conduit at each side of the hull of the boat and extending both fore and aft, the upper and lower walls of such forwardly and rearwardly extending parts being continued inward to join the hull of the boat for 100 providing water-collecting and water-discharging funnels respectively at the bow and at the stern of the boat, the hull of the boat forming one of the walls of each conduit and all of the other walls thereof being parallel to the longitudinal axis of the boat. 105

22. A device for decreasing the head resistance of boats comprising a water-conveying conduit at each side of the hull of the boat and extending both fore and aft, 115 the upper and lower walls of such forwardly and rearwardly extending parts being continued inward to join the hull of the boat for providing water-collecting and water-discharging funnels respectively at the bow and at the stern of the boat, the hull of the boat forming one of the walls of each conduit and all of the other walls thereof being parallel to the longitudinal axis of the boat, 120 and means for impelling the water sternward through such conduits. 125

23. A device for decreasing the head resistance of boats comprising a water-con-

veying conduit at each side of the hull of the boat forming a hollow bilge-keel extending substantially from stem to stern and open fore and aft.

- 5 24. A device for decreasing the head resistance of boats comprising a water-conveying conduit at each side of the hull of the boat forming a hollow bilge-keel extending substantially from stem to stern and open fore and aft, and means for impelling the water sternward through such conduits.

10 25. A device for decreasing the head resistance of boats comprising a water-conveying conduit at each side of the hull of

the boat forming a hollow bilge-keel extending forward substantially to the bow and open fore and aft.

26. A device for decreasing the head resistance of boats comprising a water-conveying conduit at each side of the hull of the boat forming a hollow bilge-keel extending forward substantially to the bow and open fore and aft, and means for impelling the water sternward through such conduits.

In testimony whereof I have affixed my signature.

HUGO BRINKHAUS.
